CLAIM

The ornamental design for a bicycle cover, as shown and described.

DESCRIPTION

FIG. 1 is a top plan view of a bicycle cover showing my new design;

FIG. 2 is a right side elevational view thereof, the environmental structure shown in dotted lines being for illustrative purposes only;

FIG. 3 is a rear elevational view thereof;

FIG. 4 is a bottom plan view thereof;

FIG. 5 is a left side elevational view thereof; and

FIG. 6 is a front elevational view thereof.
